UNITED STATES PATENT OFFICE.

CHARLES F. SCHLUETER, OF MILWAUKEE, WISCONSIN.

EXTENSION-TABLE.

1,139,730.

Specification of Letters Patent.

Patented May 18, 1915.

Application filed November 17, 1913. Serial No. 801,458.

To all whom it may concern:

Be it known that I, CHARLES F. SCHLUETER, a citizen of the United States, and resident of Milwaukee, in the county of Milwaukee, 5 and State of Wisconsin, have invented certain new and useful Improvements in Extension-Tables; and I do hereby declare that the following is a full, clear, and exact description thereof.

10 My invention refers to tables, its object being to provide a simple, economical and effective self-contained extension table. The arrangement and construction of the table is such that slideable end leaves are 15 adapted to be drawn out and effect a spring-pressed joint with abutting edges of a vertically movable table-top, which top is slightly lifted when it is desired to fold the leaves and, under such conditions the 20 leaves are arranged to slide under the table-top and form a permanent flat rest therefor in conjunction with a fixed guide-frame. Thus the extra leaves are concealed when not in use and are at all times intact with 25 the table, whereby the inconvenience of storing and adjusting detached leaves is avoided.

With the above objects in view the invention consists in certain peculiarities of construction and combination of parts as hereinafter set forth with reference to the accompanying drawings and subsequently claimed.

In the drawings Figure 1 represents a longitudinal sectional elevation of a table 35 with leaves extended embodying the features of my invention, the section being indicated by line 1—1 of Fig. 2; Fig. 2, a plan view of the same with the table-top removed; Fig. 3, a side view of said table 40 showing the leaves contracted; Fig. 4, a detailed cross-section of a guide-frame, the section being indicated by line 4—4 of Fig. 3, and Fig. 5, another detailed cross-section showing a guide-rail and one of its supporting rests in connection with the table 45 apron.

Referring by characters to the drawing, 1, 1, represent a set of table legs which are connected in the usual manner by end strips 2 50 and side strips 3 constituting the table apron. The side strips 3 have secured thereto a transversely disposed guide-frame, which guide-frame comprises an anchor-board 4 and a reach-board 5 that is spaced 55 from the anchor-board and secured to spac-

ing blocks 5' which, in turn, are fast to the side strips 3. The anchor-board of the transversely disposed guide-frame is provided with a centrally arranged slot 4', into which is loosely fitted a vertically movable 60 block 6, the same being secured to the under side of a table-top 7. Hence it will be seen that the table-top is capable of vertical shift and is otherwise detached from the framework of the table. The end edges 7' of the 65 table-top are, as shown, preferably scrolled outwardly to effect a matched joint with corresponding inwardly scrolled edges 8' of table leaves 8, the said edges, as best shown in Fig. 1, forming a flush lap joint in connection with the table top when the leaves are extended. Each leaf is supported in a horizontal plane upon a pair of rails 9 having tongues 9', each pair of said rails being adapted to slide in tongue and grooved recesses 10 that are formed in the end strips 2. The pairs of rails are also obliquely disposed and inclined downwardly toward the center of the table, at which point they are supported by engagement with the under side 70 of the anchor-board 4 constituting part of the guide-frame. The rails are also limited as to vertical play by the reach-board 5, between which reach-board and the anchor-board they are adapted to travel in oppositely inclined oblique planes. Each rail has secured thereto a one-piece bracket 11 provided with outwardly extended apertured feet 11' for the reception of a plunger 12 having a buffer-head 12', which buffer-head is adapted to engage the inner face of a juxtaposed end strip 2 when the leaves are extended. Each plunger carries a pin 13, between which and the inner bracket ear there is interposed a coiled spring 14 whereby the 75 plungers are maintained under spring pressure.

When the table leaves are extended as shown in Fig. 1, it will be observed that the table-top rests upon the anchor-board 4 of 80 the guide-frame and that its end edges which are matched with the corresponding edges of the leaves rest upon the upper surfaces of the rails, whereby the table-top is firmly seated. It will also be observed that, 85 prior to the joint being effected between the table-top and leaves, the heads of the plungers engage the end strips 2 of the apron, whereby the coiled springs are compressed and hence, after each leaf has been drawn 90 95 100 105 110

out to permit the table-top to drop to its seat, the spring-controlled plungers will exert force to contract the leaves, whereby a constant pressure is maintained at each joint and, owing to the overlapped engagement between the edges 8' of the leaves and the table edges 7', the spring pressure also serves to hold the table-top securely in place.

To contract the leaves the operator first 10 distends the leaves slightly in opposition to the buffer-springs to open the joint between the table and after the table-top edge is exposed, the said top is tilted upwardly to permit the juxtaposed leaf to slide thereunder, which initial movement is imparted to the aforesaid leaf by its spring connections. The joint of the opposite leaf is then unlocked in a similar manner and it is apparent that at this time the table-top is resting upon the edges and has been lifted from 20 its seat upon the anchor-board but is retained from displacement by its block 6 which is in engagement with the anchor-board slot 4'. The table leaves are thereafter shoved toward the center of the table and their edges 8' will effect a joint in connection with corresponding edges of the anchor-board, in which position the leaves will be contracted within the area of the 30 table-top, as shown in Fig. 3, to thus form

a flat uninterrupted surface upon which the table-top proper rests.

I claim:

In an extension table having recessed end strips, pairs of rails in slideable union with the end strips the opposite pairs of rails having side faces in sliding contact with each other whereby they are guided, means for supporting the inner ends of the rails, a table leaf carried by each of said rails, 35 and a table-top arranged to be fitted between the leaves; the combination of brackets secured to the outer side faces of one pair of the rails and to the inner side faces of the companion pair of rails, and spring-controlled plungers mounted in the brackets, the opposite pairs of said plungers being adapted to pass each other when the rails are contracted and to engage the end strips 40 at four points when said rails are distended, 45 whereby a draw pressure is exerted upon the four points mentioned.

In testimony that I claim the foregoing I have hereunto set my hand at Milwaukee in the county of Milwaukee and State of 50 Wisconsin in the presence of two witnesses.

CHAS. F. SCHLUETER.
